United States Patent Office

Des. 219,842
Patented Feb. 2, 1971

219,842

COMBINED RUBBER STAMP AND BASE THEREFOR

Harold L. Miller, 7730 Emerson Ave. N.,
Minneapolis, Minn. 55430

Filed Nov. 17, 1969, Ser. No. 20,126

Term of patent 14 years

Int. Cl. D18—99

U.S. Cl. D64—10

FIG. 1

FIG. 3

FIG. 2

FIG. 4

FIG. 5

FIG. 6

FIG. 1 is an isometric view of a combined rubber stamp and base therefor showing my new design;

FIG. 2 is an exploded isometric view thereof showing the cover, stamp and base in separated position;

FIG. 3 is a front elevation of the combined rubber stamp and base therefor;

FIG. 4 is a top plan view thereof;

FIG. 5 is a rear elevation thereof; and

FIG. 6 is a left hand end elevation thereof.

I claim:

The ornamental design for a combined rubber stamp and base therefor, substantially as shown.
